Inventor

Joseph Peyser

By his Attorney

Frank B. Beekman

UNITED STATES PATENT OFFICE.

JOSEPH PEYSER, OF MOUNT VERNON, NEW YORK.

SEAMING TOOL.

Application filed October 29, 1921. Serial No. 511,343.

To all whom it may concern:

Be it known that I, JOSEPH PEYSER, a citizen of the United States, and a resident of Mount Vernon, in the county of Westchester 5 and State of New York, have invented certain new and useful Improvements in Seaming Tools, of which the following is a specification.

The present invention relates generally to 10 seaming mechanism and has for its main object and purpose the provision of means whereby more time will be given in which to perform the in and out movement of the seaming tools.

15 In devices of this character it is, under certain conditions, desirable to use two first operation seaming tools and two second operation seaming tools. To avoid undue crowding of the parts I employ two separate 20 concentric seamer cams, one for actuating both of the first operation seaming tools and the other for actuating both of the second operation seaming tools.

The invention may be embodied in a construction in which the container to be seamed rotates and the seaming tools are relatively stationary; or, as in the present case, the container may be stationary and the seaming tools may revolve around the work. In either event, the two seamer cams 25 have an effective circumferential displacement of one revolution with respect to the seamer head, which condition may be obtained either by having the seamer head stationary and the cams making one revolution 30 to each seaming cycle, or by rotating both the seamer head and cams, say, in the proportion of fifteen to sixteen revolutions to each cycle of the machine.

35 In the accompanying drawings, the invention is disclosed in a concrete and preferred form in which:

Fig. 1 is a vertical sectional view on the plane of irregular line 1—1 of Fig. 2 40 through a seamer head embodying the invention.

Fig. 2 is a top plan view of the parts shown in Fig. 1 partly in section.

Fig. 3 is a vertical sectional view on the 45 plane of line 3—3 of Fig. 1.

1 indicates a chuck which is the complement of the usual pedestal (not shown) and which in this case is non-rotating. 2 is the seamer head rotated by means of suitable

gearing (not shown) and carrying first and 55 second operation seaming tools 3 and 4. Two concentric annular cams 5 and 6 are provided consisting in this instance of two cam grooves cut in a single member 7, and this member is keyed to sleeve 8 rotated at 60 a differential speed with relation to the seamer head. The seamer head is provided with four radial guides arranged in two sets 9 and 10, the members of each set being diametrically opposed to each other, and the 65 members of the two sets being at right angles to each other. Each of said guides contains a slide 11 which carries a seaming tool. Each of the slides carries a cam roller, two of the cam rollers 12 engaging with first 70 operation seaming cam 5 and the other two cam rollers 13 engaging with the second operation seamer cam 6.

During rotation of the parts the two oppositely disposed first operation seaming 75 tools 3 will first move inwardly and seam the work, the second operation seaming tools 4 being in their outermost position; and thereafter the two second operation seaming tools 4 move inwardly to complete the seaming 80 operation while the first operation seaming tools move outwardly. During the period when the cams move the tools into neutral position the container is removed from engagement with the chuck and another container placed in position. The parts 14 of the second operation seamer cam which are adjacent to the active portions of the cam 85 are rendered elastic by cutting away a portion of the metal as shown to permit the second operation rollers to pass over the extra thickness of metal at the longitudinal seam 90 of the body of the container. Any suitable means may be used to adjust the position of the seaming tools to permit the machine to 95 be employed to seam different sizes of containers. In the present instance each seaming tool is carried by an eccentric member 15 seated in an opening 16 in slide 11, and by turning this eccentric member the seaming 100 tool can be adjusted. The means for effecting turning movement of the eccentric member consists of a sleeve 17 connected with the eccentric member by means of pin 18, and 19 indicates a number of wrench 105 sockets for turning sleeve 17. When the parts have been properly positioned bolt 20 is turned thereby clamping the parts to-

gether. Spindle 21 of the cam roller is carried by a plate 22 removably seated in recess 23 of the slide.

I claim:

- 5 1. Seaming mechanism comprising: a seamer head, two diametrically opposed first-operation seaming tools slidingly mounted on said seamer head, two diametrically opposed second-operation seaming tools
10 also slidingly mounted in the seamer head but at right angles to the first-operation seaming tools, two concentrically disposed seaming cams disposed within the seamer head, separate connections from the two
15 first-operation seaming tools to one of said cams to operate said first-operation seaming tools in unison, and separate connections from the two second-operation seaming tools to the other of said cams to operate the sec-
20 ond-operation seaming tools in unison.

2. Seaming mechanism comprising: a

chuck, a seamer head, two first-operation seaming tools, two second-operation seaming tools, two concentrically disposed seaming cams arranged in the same plane, means for 25 actuating the first-operation seaming tools from one of said cams, and means for actuating the second-operation seaming tools from the other of said cams.

3. Seaming mechanism comprising: a 30 chuck, a seamer head, a plurality of seaming tools, two concentrically disposed seaming cams arranged in the same plane, means for actuating one of said seaming tools from one of said cams, and means for 35 actuating another seaming tool from the other of said cams.

Signed at New York city, in the county of New York and State of New York, this 27th day of October 1921.

JOSEPH PEYSER.
